US00D507384S

(12) **United States Design Patent** (10) Patent No.: **US D507,384 S**
Tsuruha et al. (45) Date of Patent: **** Jul. 12, 2005**

(54) COMBINED DISH WASHING MACHINE AND DRYING MACHINE	JP	D916708	1/1995
	JP	D1006257	3/1998
	JP	D1006257/1	3/1998
(75) Inventors: Toshiaki Tsuruha, Ikoma (JP); Masaru Kobayashi, Nara (JP)	JP	D1072792	6/2000
	JP	D1103007	3/2001
	JP	D1141692	5/2002
	JP	D1157937	11/2002
	JP	D1169620	4/2003

(**) Term: **14 Years**

* cited by examiner

(21) Appl. No.: **29/201,842**

Primary Examiner—Louis S. Zarfas

(22) Filed: **Mar. 22, 2004**

Assistant Examiner—John Windmuller

(30) **Foreign Application Priority Data**

(74) Attorney, Agent, or Firm—Brinks Hofer Gilson & Lione

Oct. 6, 2003 (JP) 2003-029301

(57) **CLAIM**(51) LOC (8) Cl. **15-05**

We claim the ornamental design for a combined dish washing machine and drying machine, as shown and described.

(52) U.S. Cl. ..... **D32/3****DESCRIPTION**(58) **Field of Search** D32/1-3, 5, 6,
D32/8, 25, 28; D7/340, 405, 348-351;
68/212; 312/31, 228, 228.1, 204; 134/113,
201, 57 D, 57 DL, 56 D, 58 D, 56 DL

FIG. 1 is a top perspective view of a combined dish washing machine and drying machine of the present invention;
